UNITED STATES PATENT OFFICE.

JAMES F. McELROY, OF ALBANY, NEW YORK, ASSIGNOR TO CONSOLIDATED CAR-HEATING COMPANY, OF ALBANY, NEW YORK, A CORPORATION OF WEST VIRGINIA.

AUTOMATIC TRAIN-HOSE COUPLING

959,152.

Specification of Letters Patent. Patented May 24, 1910.

Application filed February 14, 1907. Serial No. 357,282.

To all whom it may concern:

Be it known that I, JAMES F. McELROY, a citizen of the United States, residing at Albany, in the county of Albany and State 5 of New York, have invented certain, new and useful Improvements in Automatic Train-Hose Couplers, of which the following is a specification.

This invention relates to straight-port automatic pipe-couplers for railway-cars in which the port-faces are transverse to the longitudinal line of the car and the pressure for holding mating heads in contact is exerted along said longitudinal line.

15 My invention provides an improved combination of guiding horns whereby the heads are brought into and kept in contact as well as certain improved details of construction more fully pointed out hereinafter.

20 Of the accompanying drawings, Figure 1 represents a perspective view of one of my improved coupler-heads applied to the end of a car. Fig. 2 represents a side elevation showing two coupler-heads connected together.

25 Fig. 3 represents a plan view of the connected coupler-heads. Figs. 4 to 8 inclusive represent detail views of one of the coupler-heads, Fig. 4 being a plan, Fig. 5 an elevation of the latch side, Fig. 6 an end view, Fig. 7 an elevation of the side opposite the latch, and Fig. 8 a horizontal view partly in section to show the latch spring.

10, 10 are the draw-bars of two connecting cars with car-couplers 11, 11 on the ends 35 thereof.

12, 12 are brackets fixed to the draw-bars for supporting the pipe-couplers and inclined downwardly and forwardly.

The manner of attaching bracket to draw- 40 bar by means of staples 13 shown at the left of Fig. 2 is preferred as avoiding perforation of the draw-bar. Mounting the pipe-coupler heads directly on the draw-bars causes the heads to be automatically brought 45 into alinement by the action of coupling the cars, and thus reduces very considerably the necessary width of the guiding-wings or horns provided on the pipe-coupler heads.

The pipe-coupler heads are represented at 50 14, 14 and each is mounted at the end of a bar or stem 15 movable in a socket at the lower end of bracket 12. The coupler stem and socket are each plane-faced or rectangular, but sufficient play is permitted to allow 55 for a slight twisting motion and more or

less universal angular swing of the heads to compensate for relative movements of cars. Each stem has a rear shoulder 16 to limit the forward movement of the head, and a heavy spring 17 surrounds said stem between the 60 coupler-head and the bracket 12 to normally force the coupler-heads beyond the meeting line of the cars and furnish the requisite pressure to overcome the separating action of the fluid pressure at the gasket faces and 65 maintain fluid-tight joints. The lower end of each bracket 12 is recessed to accommodate the rear end of the spring. Each coupler-head is suspended by a chain 18 from a flat spring-arm 19 attached to the bracket 70 12 whereby the weight of the heads is flexibly sustained.

20, 21, 22 are the flexible hose connections of the various train-pipes, such as steam, air-brake, and air-signal, attached to 75 branches which are cast with the heads 14, and terminating in a vertical row of gaskets 23, 24, 25 on the connecting faces of the heads.

Each head 14 has on one side a pair of 80 fixed guiding-wings or horns 26 for bringing the complementary gaskets into alinement, said horns having their outer ends flared or slanted to the line of coupling movement for affording the requisite shearing or cam action, and furthermore at the root of each horn is an abutment or shoulder 85 27 parallel to the coupling movement. Preferably the horns are extended as shown somewhat over and under as well as at the 90 side of the space for the entrance of the mating coupler-head so as to afford alinement in a vertical as well as a horizontal direction.

On the side of each head, opposite the 95 space between the fixed horns 26 is mounted a yielding locking member or horn in the form of a latch 28 pivoted on a hinge 29 at its rear end and having a flared or slanting portion 30 at its forward end. The latch is 100 engaged between its two ends by the head of a lateral bolt 31 having a spring 32 which occupies a socket in the coupler-head and swings the latch inwardly against the body of said head. The latch is also formed with 105 V-shaped recesses 33 on opposite sides of a horizontal alining rib 34 and each head has a pair of complementary V-shaped lugs or projections 35, located on the opposite side from the latch between the horns 26 and 110

adapted to occupy the recesses 33 in the latch of the complementary coupler-head. These projections are separated by a space to receive the alining-rib 34 of the complementary latch.

The special arrangement of fixed horns, movable horn or latch, and latch-locking projections, wherein the latch is located opposite the space between the fixed horns, and 10 the V-shaped projections are situated in said space, affords a compact and otherwise advantageous disposition of the parts. The three-pronged arrangement of horns balances side-thrusts so that no twisting strain 15 is imparted when the heads come together.

When cars equipped with these pipe-coupler heads are brought together the inclined faces of the fixed horns and the movable latch operate to secure a proper alignment of the port faces into a "straight-port" coupled relation, and the heavy springs 17 yield to permit this engagement and furnish the endwise pressure which holds the gaskets together in a fluid-tight 20 relation. The spring-latch 28 on each coupler-head yields during this engagement and snaps over the retaining projections 35 on the opposite head so that when fully engaged the latches act in a capacity auxiliary 25 to the main springs 17, maintaining a permanent and fluid-tight engagement between the heads. They also cooperate with the fixed abutments or shoulders 27 in preserving 30 a horizontal alinement of the gaskets without tendency to longitudinally separate 35 the heads, and these shoulders furnish a part of the lateral resistance which displaces the latch of the opposite coupler-head and causes it to effect its proper engagement. The inclined shape given to the recesses 33 and 40 projections 35 assists in drawing and keeping the coupler-heads together.

I find that the presence of the yielding latch mounted and related to the parts as 45 described results in tighter fluid-joints and easier and more accurate connection and release of the coupler-heads, and the presence of the latch reduces the strength which it has heretofore been necessary to impart to 50 the main spring 17. When the cars separate, the stop-shoulders 16 bring up against the brackets 12 and effect an automatic dis-

connection of the coupler-heads, at which time the latches 28 will automatically yield and become unlocked.

55

I claim,—

1. A straight-port automatic train-pipe coupler head having an abutting port-face substantially at right-angles to the line of thrust, means for yieldingly urging said coupler-head in a direction at right-angles to its port face to maintain a fluid-tight joint with the mating head, a pair of flared guiding horns on one side of said port-face, and a yielding flared guiding horn on the other side of said face opposite the space between the first-said horns.

2. A straight-port automatic train-pipe coupler head having a port-face at right-angles to the line of thrust, a guiding horn on one side of said port-face having a longitudinal shoulder at its base at right-angles to said face and a flared end, and a yielding guiding horn located on the other side of said port-face and formed as a latch to automatically lock and unlock with the mating head and to force the latter transversely against said shoulder.

3. A coupler-head having a port face in a plane substantially at right-angles to the direction of thrust, a pair of fixed guiding horns on one side of said port face, a yielding latch hinged at its inner end on the other side of said port-face opposite the space between said fixed horns, and spring mechanism for laterally pressing said latch inwardly.

4. A pipe-coupler-head having a port face with a pair of V-shaped latch-engaging projections arranged on one side thereof with a space between them, and a yielding spring-latch on the opposite side of said port face formed with V-shaped recesses to receive the corresponding projections of a mating coupler-head, and an alining-rib between said recesses adapted to enter the space between the projections on the mating coupler-head.

In testimony whereof I have hereunto set my hand in the presence of two subscribing witnesses, the 9th day of February, 1907.

JAMES F. McELROY.
